UNITED STATES PATENT OFFICE.

JOHN T. GARDNER, OF HAMILTON, OHIO, ASSIGNOR TO THE DEFIANCE MACHINE WORKS, OF DEFIANCE, OHIO.

WHEEL-ASSEMBLING MACHINE.

1,304,676.

Specification of Letters Patent. Patented May 27, 1919.

Application filed August 29, 1918. Serial No. 251,877.

To all whom it may concern:

Be it known that I, JOHN T. GARDNER, a citizen of the United States, residing at Hamilton, Butler county, Ohio, have invented 5 certain new and useful Improvements in Wheel-Assembling Machines, of which the following is a specification.

This invention relates to improvements in machines for assembling spoked wooden 10 wheels, and the improvements will be readily understood from the following description taken in connection with the accompanying drawings in which:—

Figure 1 is a front elevation of a machine 15 embodying my improvements, duplicated parts being omitted:

Fig. 2 a vertical section of the lower portion of the same, in the plane of line *c* of Fig. 3:

20 Fig. 3 a plan of the table, parts appearing in horizontal section in the planes of lines *b* and *c* of Figs. 1 and 2, certain portions being broken away:

Fig. 4 a plan of half of a wheel, ready for 25 assembling:

Fig. 5 an elevation of a clamp-hub: and

Fig. 6 an elevation of one of the shims.

A diversity of scales is employed in the drawings.

30 In the drawings, referring particularly to Figs. 4 and 5:—

1, indicates a half of the felly of such a wooden wheel as is commonly employed in automobiles, for instance:

35 2, the spokes tenoned into the felly and making contact at their central portions on radial lines:

3, the flat faces of the central portions of these spokes:

40 4, the bore of the wheel:

5, a tube, forming a part of a clamp-hub, loosely entering the bore of the wheel: and

45 6, a flange on the lower portion of the tube, this flange, together with another loose flange and a nut on the tube forming a clamp-hub to engage the faces at the center of the spokes after the wheel has been forced into assemblage.

The felly halves having been produced, 50 and their ends jointed, and the spokes having been produced and formed accurately with their radial joint surfaces, and having been driven into the felly halves, there are in hand two loose wheel halves. It becomes 55 the duty of the wheel-constructor to as-

semble these two halves and to compress the felly radially into a true circle with the radial joints between the spokes pressed into forceful contact, and to so hold the central portion of the spokes while a tire is being applied to the felly. After the wheel has been assembled, in the manner stated, and while it is still under radial compression, a clamp-hub, such as is shown in Fig. 5, is applied, and the nut screwed down tightly, 60 before the assembled wheel is relieved of its radial compression. After the clamp-hub is applied then the radial pressure may be removed and the assembled wheel provided with its tire, after which the clamp-hub, having performed its temporary duty, 65 may be removed for further use. The present machine has to do with the application of the radial pressure to the wheel being assembled and to the applying of the clamp-hub thereto.

Continuing with the drawings:—

7, indicates a sole-plate:

8, a table provided with radial dovetailed slots and having an open center margin by a strong ring:

9, legs supporting the table, from the sole-plate:

10, a jaw fitted to slide in each of the slots of the table:

11, the separable inner facing of these jaws:

12, removable shims of various thicknesses which may be placed between the jaws and the facings:

12^a, studs fixed to the facings and sliding in holes in the jaws, the shims being slotted to straddle these studs:

13, a cylindrical stump having its base secured to the sole-plate under the center of the table, and having its upper end provided with cup-leather packing:

14, a closed-topped cylinder:

15, a series of eye-bolts, one for each of the dovetailed slots in the table, screwed 100 radially into the central ring of the table and projecting outwardly beyond the table:

16, a vertical lever pivoted to the outer end of each of these eye-bolts:

17, a link pivoted to the foot of each of 105 these levers and having its inner end pivoted between lugs projecting from the base of the cylinder:

18, a link pivoted to the upper end of each of the levers and having its inner end piv- 110

- oted in one of the jaws sliding radially on the table:
- 19, an annular anvil threaded vertically into the center of the table:
- 5 20, blocks resting on the table, around the anvil, and adapted to support the felly of the wheel being assembled:
- 21, a fixed cylindrical stump rising from the center of the head of cylinder 14 and 10 provided with cup-leather packing at its upper end:
- 22, a pin rising from the center of stump 21 and adapted to have the tube of the clamp-hub placed loosely upon it, together 15 with its lower clamp-flange:
- 23, a cylinder fitted to slide on the stump 21, and provided with packing around pin 22, this cylinder being hereinafter termed the auxiliary cylinder:
- 20 24, a flexible pipe connecting with the top of the auxiliary cylinder, this pipe being preferably in the form of a hose coiled about the auxiliary cylinder:
- 25 25, a three-way cock in this pipe:
- 26, fixed housings rising from the table:
- 27, a cross-beam supported by these housings:
- 28, a downwardly open socket-wrench mounted on the lower end of a spindle journaled on the cross-beam and arranged to be turned by power and arranged to rise and fall:
- 30 29, vertical guides, at least three in number, fixedly supported below the table around the upper portion of cylinder 14:
- 35 30, blocks secured to the upper portion of the cylinder 14 and closely fitting the vertical guides:
- 31, a pipe communicating with the upper 40 portion of cylinder 14: and
- 32, a three-way cock in pipe 31.
- Assume the jaws to be in their outer position and the cylinders in their lowermost positions. Blocks 20 are to be of such height 45 as to support the felly with its vertical center about in line with the pivots of links 18, and the anvil is to be so adjusted as to give proper support to the inner portions of the spokes when the felly is resting on the 50 blocks.
- The tube of the clamp-hub, together with its lower flange, is to be applied to the pin 22, resting upon the auxiliary cylinder.
- Compressed air, or other pressure-fluid, 55 is now to be admitted to cylinder 14, by manipulating cock 32, whereupon cylinder 14 is forced upwardly and the jaws forced inwardly, thus radially compressing the wheel-parts being assembled. The application 60 of the pressure-fluid is to be arrested when a mild degree of contacting pressure has been put on the radial joints between the inner portions of the spokes. While the inner portions of the spokes may have been 65 faced off they may not be flush with each
- other, but a little downward driving will bring them all down nicely upon the anvil, the friction due to the radial pressure thus far applied being sufficient to hold the spokes after they have been driven down. The 70 pressure of the fluid may now be increased, the result being that the inner joints between the spokes are forced into exceedingly firm contact, even to a point of compression of the wood. This completes the assembling 75 of the wheel parts, ready for the temporary application of the clamp-hub, so that the assemblage may be removed from the machine.
- When cylinder 14 made its rising stroke, in applying radial pressure to the wheel, it 80 carried the clamp-hub up with it and may have poked the tube more or less into the central bore of the wheel. Upon the completion of the radial pressure then, by manipulating cock 25, pressure-fluid is to 85 be admitted to the auxiliary cylinder, which cylinder at once rises and carries the clamp-hub clear up, though not necessarily pressing its lower flange forcefully against the wheel center. The upper flange of the 90 clamp-hub is now to be placed on the tube and the clamp-nut started on the tube, after which the socket-wrench is to be lowered upon the nut and set into motion, the result being that the two flanges, which are to be 95 circumferentially corrugated upon their faces, clamp the sides of the spokes firmly between them so as to prevent the radial retraction of the spokes. The assemblage is now complete and the pressure-fluid may be 100 released from each of the cylinders, whereupon both cylinders descend, the pin drawing out of the clamp-hub, and the jaws retreating radially from the wheel. The wheel with its temporary clamp-hub, may now be 105 removed for subsequent treatment.
- Before starting in to assemble the parts of the wheels of a given lot, the blocks 20 of proper height, are to have been provided, and a proper adjustment of the jaws is to 110 have been made to cause the jaws to move to a circle of proper diameter, which adjustment may be effected by selection of pivot-holes in links 18, or by selections of shims 12 of proper thickness between the jaws and their facings, or both methods of adjustment may be involved.
- While the cylinder 14 is rising on its stump it is guided by the stump, but as the cylinder rises the effective guiding surfaces 115 as effected by the stump becomes shorter; and the upper portion of the cylinder might be forced more or less sidewise so as to displace the central pin. But in the present instance, the guides 29, are active at the top 120 of the cylinder and continue in their guiding effect throughout the elevating motion of the cylinder. The adjustment of blocks 30 permits of accurate guiding adjustment of the 125 guiding fit, so as to keep the pin central, and 130

so as to avoid side pressure of the cylinder on its cup-leather packing.

I claim:—

1. A wheel-assembling machine comprising, a radially slotted table with an open center, jaws fitted to slide radially therein, means for forcing the jaws simultaneously inward, a vertically adjustable annular anvil supported at the center of the table, a pin disposed in the axis of the anvil and adapted to support a clamp-hub, and mechanism for moving the pin and clamp-hub upwardly, combined substantially as set forth.
2. A wheel-assembling machine comprising, a radially slotted table with an open center, jaws fitted to slide radially therein, a cylinder and piston disposed axially below the table, a lever for each of said jaws and pivoted to the table and linked to the jaws, and links pivoted to the lower ends of the levers and adapted to be moved outwardly by the action of fluid-pressure in said cylinder, combined substantially as set forth.
3. A wheel-assembling machine comprising, a radially slotted table with an open center, jaws fitted to slide radially therein, a fixed stump secured axially below the table and provided with packing, a cylinder closed at its top and fitted to slide on the stump, levers pivoted to the table and having their upper ends connected with the jaws, links having their inner ends pivoted to the cylinder and their outer ends pivoted to the lower ends of the levers, and means for controlling the flow of pressure-fluid to the cylinder, combined substantially as set forth.
4. A wheel-assembling machine comprising, a radially slotted table with an open center, jaws fitted to slide radially therein, a fixed stump secured axially below the table and provided with packing, a cylinder closed at its top and fitted to slide on the stump, levers pivoted to the table and having their upper ends connected with the jaws, links having their inner ends pivoted to the cylinder and their outer ends pivoted to the lower ends of the levers, means for controlling the flow of pressure-fluid to the cylinder, and vertical guides disposed below the table and coöperating with the upper part of the cylinder, combined substantially as set forth.
5. A wheel-assembling machine comprising, a radially slotted table having an open center, jaws fitted to slide radially therein, means for moving the jaws inwardly simultaneously, a cylinder and piston disposed axially below the table, a pin disposed in the axis of the table and adapted to give support to a clamp-nut and to be moved by

the pressure of fluid acting in said cylinder, and means for controlling the flow of fluid-pressure to said cylinder, combined substantially as set forth.

6. A wheel-assembling machine comprising, a radially slotted table having an open center, jaws pivoted to slide radially in said table, mechanism for moving the jaws inwardly, a stump disposed axially below the table, a cylinder fitted to slide on said stump, a second stump mounted on said cylinder, a pin projecting upwardly from the second stump, a cylinder fitted to slide on the second stump and pin, a flexible pipe connected with the upper portion of the cylinder, and means for controlling the flow of fluid-pressure in the cylinder, combined substantially as set forth.

7. A wheel-assembling machine comprising, a radially slotted table having an open center, jaws fitted to slide radially in the table, mechanism for moving the jaws inwardly, a pin disposed axially of the table and adapted to support a clamp-hub, a lifting device for sliding the clamp-hub upwardly upon the pin, and means for elevating the pin in advance of the action of the lifting device, combined substantially as set forth.

8. A wheel-assembling machine comprising, a radially slotted table having an open center, jaws fitted to slide radially on the table, a support for a clamp-hub at the axis of the table, mechanism for simultaneously moving the jaws inwardly and elevating the support of the clamp-hub, and means for elevating the support after the jaws have come to rest, combined substantially as set forth.

9. A wheel-assembling machine comprising, a radially slotted table having an open center provided with a marginal ring, jaws fitted to slide radially on the table, eye-bolts having their inner ends screwed into said ring, levers pivoted to the outer ends of the eye-bolts, connections between the jaws and the upper ends of the levers, and mechanism for moving the lower ends of the levers outwardly, combined substantially as set forth.

10. A wheel-assembling machine comprising, a table, a jaw fitted to slide radially therein, mechanism for forcing the jaw inwardly, a facing for the jaw, studs projecting outwardly from the facing and adapted to slide in the jaw, and shims straddling the studs and disposed between the jaw and the facing, combined substantially as set forth.
